(57) **CLAIM**

The ornamental design for a camera lens barrel, as shown and described.

DESCRIPTION

FIG. 1 is a front, left, and top perspective view of a camera lens barrel showing my new design.

FIG. 2 is a rear, right, and top perspective view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front elevational view thereof; and,

FIG. 8 is a rear elevational view thereof.

The dashed-dot lines form the boundary of the claimed design and the even dashed broken lines shown in the drawings are included for the purpose of illustrating portions of the camera lens barrel, that form no part of the claimed design.
